UNITED STATES PATENT OFFICE

MARGARET E. McCCLAY AND CHARLES E. McCCLAY, OF LOS ANGELES, CALIFORNIA

VISOR

Application filed April 16, 1928. Serial No. 270,313.

This invention relates to visors and is more particularly related to a visor formed of pyralin, or similar transparent material, in a manner similar to that disclosed in the 5 patent issued to ourselves March 2, 1926, No. 1,575,219, for Sunshade. Visors formed of pyralin or similar transparent material have a tendency to curl or roll when not packed to cause the same to retain their shape. This 10 tendency to roll is particularly noticeable when the visors are displayed on counters or in windows and is particularly noticeable when the visors are displayed where the sun strikes them.

15 In forming the visors or sunshades when the bill or visor section is formed and it is desired to secure the same to the sweat band, it is necessary, in accordance with the disclosure set forth in our prior patent, to hold 20 the visor section in the proper curved relation relative to the sweat band while the visor portion is being cemented to the sweat band. In holding the visor portion in the proper curved relation to enable it to be secured to the sweat band, it is the practice to 25 steam or heat the visor portion.

We have found that all of these difficulties may be overcome, that is, the curling of the completed visor when displayed, and the 30 necessary of heating and holding the visor in the proper curved relation in order to enable it to be secured to the sweat band, if the visor is formed during the cutting of the same with longitudinally extending ribs.

35 We have found also that the visor will, when cut with the longitudinally extending ribs, of its own accord curl to the proper position in order to enable it to be secured to the sweat band and that the entire visor when 40 formed with such longitudinally extending ribs may be formed of thinner pyralin or similar transparent material, enabling the formation of a visor lighter in weight and less expensive.

45 It is therefore, an object of this invention to provide a visor including a sweat band and a visor portion or bill secured to the sweat band at the lower edge thereof, the 50 visor portion or bill being formed curved

and with a multiplicity of longitudinally extending ribs.

Another object of this invention is to provide a visor including a sweat band, a visor portion or bill, and a crown member, the 55 crown being secured to the bill and securing a sweat rim to the sweat band.

Other objects and advantages of this invention, it is believed, will be apparent from the following detailed description of a preferred embodiment thereof, as illustrated in the accompanying drawings.

In the drawings:

Figure 1 is a perspective view of a visor embodying this invention and illustrating 60 the same as adapted to the head of an individual.

Figure 2 is a side elevation thereof.

Figure 3 is a sectional edge view taken substantially on the line 3—3 of Figure 5.

Figure 4 is an exploded sectional edge view.

Figure 5 is a rear elevation with the head straps broken away.

In the preferred embodiment of this invention, illustrated in the accompanying drawings, 1 indicates a visor or bill cut in the proper shape and formed during the cutting with a plurality of longitudinally extending ribs 2 which vary in length from 75 the mid-section of the bill 1 to the edge thereof.

In order to ornament the visor, the edge of the same is formed with the hemispherical projections or circular raised portions 3. 85 A sweat band 4 is secured to the upper edge 5 of the visor at the curved projecting edge 6 of the sweat band 4 by cementing the engaging edges 5 and 6 together by means of a suitable solvent, such as acetone, alcohol, 90 or the like.

A pair of head straps 7, 7 are pivotally secured to the ends of the sweat band 4 by means of eyelets 8. The head straps 7 are adjustably secured together at their opposite 95 ends by means of a buckle 9.

A crown member 10, preferably formed of pyralin or like material is secured to the sweat band 4 and a sweat rim 11 formed of leather or like material is secured to the 100

crown member 10, as illustrated at 12. The crown member 10 and sweat rim 11 are then secured to the sweat band 4 by means of eyelets 13 which are passed through the crown member 10 and sweat band 4 at spaced points.

5 Crown straps 14 are secured to the sweat band 4 at the eyelets 13 and at their opposite ends are secured to the head straps 7, 7 by means of eyelets 15. The crown straps 14 are adjustably secured together by means of 10 a buckle 16.

The formation of the visor or bill 1 with the longitudinally extending ribs 2 is performed by means of a die which is also used 15 for the cutting of the pyralin or like material to form the bill 1. As the bill 1 is formed in the die and the die is released from the cutting position, the bill 1 assumes the proper curved position to enable it to be secured to 20 the sweat band 4. The ribs 2 reinforce the material of which the visor is formed to such an extent that the same will not curl on being exposed to the sun when displayed.

Having fully described our invention, it is 25 to be understood that we do not wish to be limited to the details herein set forth, but our invention is of the full scope of the appended claims.

We claim:

30 1. In a visor the combination of an outer band adapted to partially encircle the head of the wearer, a bill attached to the lower edge of said band, crown straps, a crown member between said crown straps and outer band, means for connecting said crown member to said crown straps and outer band, and a sweat rim covering said connecting means, said sweat rim having an up-turned edge held between said crown member and outer band.

40 2. In a visor the combination of an outer band adapted to partially encircle the head of the wearer, a bill cemented to the lower edge of said band, adjustable head straps pivotally connected to the ends of said outer band, crown straps pivotally connected to said head straps, a crown member between said crown straps and outer band, means for connecting said crown member to said crown straps and outer band, and a sweat rim adjoining said crown member and covering said connecting means, said sweat rim having an up-turned edge held between said crown member and sweat band.

50 55 Signed at Los Angeles, California, this 19th day of March, 1928.

MARGARET E. MCCLAY.
CHARLES E. MCCLAY.
